UNITED STATES PATENT OFFICE.

ISAAC E. PALMER, OF MIDDLETOWN, CONNECTICUT, ASSIGNOR TO THE I. E. PALMER CO., OF MIDDLETOWN, CONNECTICUT, A CORPORATION OF CONNECTICUT.

COUCH-HAMMOCK.

1,094,925.

Specification of Letters Patent. Patented Apr. 28, 1914.

Continuation in part of application Serial No. 721,765, filed September 28, 1912. This application filed November 6, 1912. Serial No. 729,791.

To all whom it may concern:

Be it known that I, ISAAC E. PALMER, a citizen of the United States, and a resident of Middletown, in the county of Middlesex and State of Connecticut, have invented an Improvement in Couch-Hammocks, of which the following description, in connection with the accompanying drawings, is a specification, like characters on the drawings representing like parts.

This invention relates to couch hammocks, the object thereof being to improve certain parts thereof and more particularly the frame and seating.

This application is in part a division of and is a continuation of my application Serial No. 721,765, filed September 28, 1912, now Patent No. 1,053,860, dated February 18, 1913.

In order that my invention may be clearly understood, I have disclosed a single embodiment thereof in the accompanying drawings, wherein—

Figure 1 is a view mainly in plan of a couch hammock embodying my invention; Fig. 2 is an enlarged view mainly in plan of one end of said frame, parts being broken away; Fig. 3 is an end elevation of the construction shown in Fig. 2, parts being broken away; Fig. 4 is a side elevation, parts being broken away, of the frame shown in Fig. 1; Fig. 5 is a cross sectional view upon the line 5—5 of Fig. 2; Fig. 6 is a cross section upon the line 6—6 of Fig. 2; Fig. 7 is a detail in plan showing one manner of attaching the lateral edges of the seating to the side members of the frame; Fig. 8 is a view similar to Fig. 7 of a slightly modified form of the invention; Fig. 9 is a transverse section of the construction shown in Fig. 7; Fig. 10 is a transverse section of the construction shown in Fig. 8; Fig. 11 is a detail showing a modified connection for the frame members; Fig.

Fig. 12 is a plan view of one corner of the frame and showing a detachable corner bracket applied thereto; Fig. 13 is a view in cross section and side elevation of the construction shown in Fig. 12; Fig. 14 is a front elevation of the construction shown in Fig. 12; Fig. 15 is a cross sectional view taken through the hammock frame and showing a detachable side bracket applied thereto; Fig. 16 is a plan view of the construction

shown in Fig. 15 and showing the upstanding fabric edge in section; Fig. 17 is an inside elevation of the construction shown in Fig. 15; and Figs. 18 and 19 are respectively a plan and cross sectional view of a slightly modified form of the invention shown in Figs. 7 and 8.

The frame of the hammock is preferably composed of metallic side members 1—1 and metallic end members 2—2, the former being represented as cylindrical or tubular and the latter as angular. The construction of the metallic end members is shown more clearly in Figs. 5 and 6, wherein the upstanding edge or flange of an end is represented at 3, and the inwardly extending web 4 or flange thereof is indicated at 4. The adjacent terminals of these members are connected together in a manner to be more fully hereinafter described.

The frame is provided with any suitable seating, such, for example, as one formed of wire links or rope or cloth. I have herein represented a seating composed of wire links 5 arranged in triangular form and connected to the plates 6, but it is to be understood that any other suitable seating may be employed. The seating is herein shown as connected to the end members 2 of the frame by coiled springs 7, the ends 8 whereof take into perforations 9 in the inwardly extending web 4 of the end members of the frame. The web or flange of each end member is inclined or upwardly extended as indicated most clearly at 10 in Fig. 6, in order to place the seating more nearly central with respect to the top and bottom edges of the web or flange 3 and also to bring the line of strain of the seating more nearly central with respect to said points. This result may be effected by bending the web 4 throughout the greater portion of its length,—that is, throughout the transverse extent of the seating. The lateral edges of the seating are connected in any suitable manner to the side members of the frame, but preferably by means of pieces encircling or substantially encircling said side members 1.

In Figs. 7 and 9, I have represented a thin resilient steel band 11 encircling the side member 1 and provided at its ends with holes 12, through which and the adjacent eye of the plate 6 is passed a suitable band,

wire or pin 13. While within the scope of my invention I may provide a wire in lieu of the band 11, I find the latter preferable and may connect it in any suitable manner to the seating. For example, in Figs. 8 and 10, I have represented the metallic band 11 as connected by a wire 14 to one of the longitudinally extending links 5 of the seating. When the seating is subjected to the strain of use, the resilient metallic bands 11 turn somewhat upon the side members 1, and thus permit the side edges of the seating to yield downwardly. When the seating is relieved of the strain of use, the parts assume the position shown in Figs. 7 to 10 inclusive, and the bands 11 are then relieved of all strain, the seating then extending in a plane intersecting substantially the horizontal axis of the side members 1 of the frame. Any suitable number of bands 11 may be employed at each side of the frame. Preferably I employ three or four at each side of the frame. The hammock may be provided with any suitable body.

In Figs. 1, 3 and 5, I have represented the hammock as provided with sheet-like preferably cloth ends 15 having at their upper ends pockets in which are mounted suitable spreaders. If desired, the said ends 15 may constitute the true suspension ends and may be provided at their upper ends with cords arranged at suitable intervals along the spreader and serving to support the hammock. Preferably, however, I provide suspension strands here shown as chains 16. When using chains, I preferably employ four, one extending upwardly from each corner of the hammock frame, and at the upper ends thereof may provide suitable rings by which the hammock may be suspended. Instead of providing suspension chains, I may provide other suitable suspension strands, such as cords or the like. The ends 14 of the hammock may be unitary with each other or connected together, as in the so-called Gloucester hammock, but preferably I terminate each end 14 at the adjacent end of the frame; and for this purpose have here represented one of said ends as having therein a pocket 17 receiving a spreader 18 connected by means of hooks 19 and bolts 20 to the web 4 of the end member 2 of the frame. The bolts 20 may, if desired, be omitted, thus permitting the hooks 19 to be readily removed from the frame. By reason of the fact that the webs 4 of the end members 2 of the frame are upwardly bent, the said webs 4 and the spreaders 18 may lie flatwise as indicated in Fig. 5.

Heretofore, as disclosed in my Patent No. 944,814, I have provided corner brackets rigidly attached to the frame, said brackets affording back pieces or supports against which the upstanding fabric sides of the hammock body may be drawn tight. In this

manner I secure well defined and preferably rectangular corners at the meeting ends of the side and end members of the frame. This member is, however, substantially above the frame, and although very effective for its purpose may become damaged in packing or transportation. To avoid this objection, I provide elongated metallic links 21, shown most clearly in Figs. 3 and 4. Each link 21 is provided at its upper end with a hooked end 22 to engage the lower end of the adjacent suspension chain 16, and at its lower end is provided with a hook 23 taking into a suitable perforation 24 at a point preferably so close to the extreme end of the web 3 that when the hammock is suspended, the outer edge 25 of the link 21 is in alignment with or forms a continuation of the vertical end edge of the said web 3, as clearly indicated in Fig. 3. Moreover, the said link is positioned closely against the outer face of the web 3, as shown in Fig. 4, so that when the hammock is supported the said links 21 form backing members or supports against which the fabric sides and ends of the hammock may be drawn tight.

If desired, I may provide the hammock with upstanding cloth or other sides 26, the ends of which meet the vertical edges of the ends 14, to which they may be connected by cords passing through gromets or in any other suitable manner. These upstanding sides 26 may be connected to the frame in any suitable manner, as, for example, by means of staples 27 permitting the ready removal of said upstanding sides from the frame. It will be evident that the ends 14 and upstanding sides 26 may be tightly secured together and that the links 21 will provide rectangular corners at the meeting edges thereof. The said links 21, when the hammock is not suspended, assume a horizontal position, the eyes 23 turning in the holes 24 for this purpose. In such position of the parts, the said links 21 do not project substantially above the upper edge of the frame.

I have previously stated that the side members of the frame are composed of cylindrical and preferably tubular metallic members 1. In order to secure the side and end members of the frame rigidly together and to accomplish this result inexpensively and yet satisfactorily, I provide the end members of the frame with some suitable formation extending out of the plane of the upper surface of the flange or web 4 thereof. Preferably I so bend the terminal portions of the webs 4 as to form slight recesses 28, into which the cylindrical side members 1 are seated. By providing a suitable recess or other supporting formation, I am enabled to secure the side and end members rigidly together by means of a bolt 29 or the like at each corner of the frame. Each

bolt passes through the meeting ends of the members 1 and 2 of the frame. While I prefer to provide recesses 28 to receive the ends of the side members 1 of the frame, I 5 may provide projections integral with said end members and extending upwardly from their upper faces, against which the said side members take and are held by the bolts 29.

10 An important feature of my invention consists in the knock down character of the frame. To that end, I may employ, instead of the bolts 29 which provide a permanent union of the end and side members of 15 the frame, screws and nuts 30, 31, as indicated in Fig. 11.

I contemplate the employment of corner brackets and side brackets to be detachably applied to the frame and having portions 20 to be engaged and held in position by the seating. Although I have herein shown the said brackets as applied to metallic frames, it is to be understood that they may be applied to frames partly or wholly formed of 25 wood or other non-metallic material. In my Patent No. 944,814, I have disclosed corner brackets which are directly secured to the wooden frame. Where, however, the frame is of metal, it is in certain cases objectionable to secure the bracket directly thereto. Therefore, I have herein shown brackets adapted to rest upon or against the members of the frame and to engage and be held in position by the seating.

30 In Figs. 12, 13 and 14, I have represented a wire bracket 32 having a general right- 35 angular form above the frame but with a curved corner. This bracket is provided at one end with a hook 33 adapted to engage 40 the hooked end 22 of the link 21. The wire 32 where it meets the tubular side member 1 of the frame is bent or curved as indicated at 34, so as to fit closely thereto throughout any desired circumferential extent. I have herein represented the wire 45 32 as resting upon the member 1 throughout substantially ninety degrees of the circumferential extent of said member. Beyond the bent portion 34 the wire is straight

50 as indicated at 35 in Fig. 12 and extends substantially to the nearest spring 7 where it is sharply bent into a shoulder 36 and terminates in an end 37 which passes through the terminal eye of the spring 7. 55 The said wire 32 is firmly held in position by reason of the engagement of its eye 33 with the hooked end 22, by reason of the curved portion 34 resting upon the member 1 of the frame, and by reason of the insertion 60 of the end 37 in the hooked end of the spring 7. The shoulder 36 prevents the wire 32 from moving inward off the frame member 1, and its movement along or axially of the member 1 is prevented by the 65 hook 33 and the eye of the spring 7. The

upstanding side of the hammock at the point where it is secured to the upstanding end thereof is held in upright or vertical position by the said corner bracket 32. In Figs. 15, 16 and 17, I have represented a similar 70 bracket adapted to be applied to the side members 1 of the frame intermediate the ends thereof and to take into pockets 38 of the upstanding sides 39 of the hammock body or to take against the inner faces of 75 the upstanding sides. The bracket shown in said figures is of a general rectangular form. It is bent at substantially mid-length into an upstanding inverted U-shaped portion 40, and each member extending from 80 said portion 40 is provided with a curved portion 41 resting upon and conforming to the contour of the side member 1 of the frame. Beyond said curved portion 41, the two portions are continued straight, as indicated at 85 42 and are then bent to provide shoulders 43 which take against the links 5, as illustrated in Fig. 16. The wires are bent beyond the shoulders 43 at substantially right angles as indicated at 44, and 90 pass through the eyes of said links 5 close to or against the plates 6. The shoulders 43 prevent the inward movement of the said brackets from off the tubular members 1, and the eyes of the links 5 prevent their 95 displacement axially along said frame members 1 in either direction. It is, of course, to be understood, that the brackets herein shown may be applied to angle members of frames by bending said brackets in conformity with the shape of the angle iron or the flange thereof. Moreover the bracket can be applied to a wooden frame or frame having a substantially flat face by suitably bending the wire. 100

105 In Figs. 18 and 19, I have shown a slightly modified form of the construction shown in Figs. 7 and 8. Therein the bands 11 terminate short of the plates 6, and short links or eyes 45 are provided to connect the bands 11 to the plates 6.

This application is in part a division of my co-pending application Serial No. 721,765, filed September 23, 1912.

Having thus described one illustrative 115 embodiment of my invention, I desire it to be understood that although specific terms are employed, they are used in a generic and descriptive sense and not for purposes of limitation, the scope of the invention being set forth in the following claims.

Claims.

1. A frame for a couch hammock consisting of tubular, straight, side members and straight, angle iron end members connected 125 at their meeting ends and positioned in the same plane, the horizontal webs of said angle irons being downwardly bent at their ends to provide recesses for the side members of the frame, and the intermediate por- 130

tions of said webs being upwardly deflected, a single bolt passing through the end of each side member and the recessed portion of the meeting web, and a seating having 5 end springs connected to said upwardly deflected portions of the web, and spring bands encircling said side members of the frame and connected to the sides of the seating, whereby the seating and members of the 10 frame are supported in the same plane.

2. A frame for a couch hammock comprising substantially cylindrical side members, transverse end members connected thereto, a seating secured to the end members 15 of the frame, and fastening devices encircling said side members, said devices being connected to the lateral edges of the seating.

3. A frame for a couch hammock consisting of an angle iron end members, and side 20 members connected to the terminals of the end members, one of the webs of each end member being substantially upright and the other extending inwardly and having an 25 up-turned edge substantially the entire distance between the side members, and a seating having end springs connected to said up-turned edges.

4. A frame for a couch hammock consisting of angle iron end members, and side 30 members connected to the terminals of the end members, one of the webs of each end member being substantially upright and the other extending inwardly and having an 35 up-turned edge substantially the entire distance between the side members, a spreader connected to the under side of the inwardly extending web of each end member, said spreaders having suspension means extending 40 therefrom, and a seating having end springs connected to said up-turned edges.

5. A frame for a couch hammock consisting of angled, metallic end members, and side members connected to the terminals of 45 the end members, one of the webs of each end member being substantially upright and the other extending inwardly and having an up-turned edge substantially the entire

distance between the side members, and having their upper surfaces transversely recessed for the reception of the terminals of the side members, and a seating having end springs connected to said up-turned edges. 50

6. A frame for a couch hammock consisting of angle iron end members, and side 55 members connected to the terminals of the end members, one of the webs of each end member being substantially upright and the other extending inwardly and having an up-turned edge substantially the entire 60 distance between the side members, the terminals of the inwardly extending webs being bent into transverse recesses for the reception of the side members, bolts penetrating the terminals of the side members and 65 said recessed terminals of the end members, and a seating having end springs connected to said up-turned edges.

7. A frame for couch hammocks comprising 70 tubular metallic side members, transverse end members connected thereto, a seating secured to the end members of the frame, and movable metallic spring bands encircling said side members, said spring bands being connected to the lateral edges of the 75 seating.

8. A frame for a couch hammock consisting of angle-iron end members and side members connected to the terminals of the end members, one of the webs of each member being substantially upright and the other extending inwardly, the terminals of the inwardly extending webs being bent into transverse recesses for the reception of the side members, bolts penetrating the terminals of the side members and said recessed terminals of the end members, and a seating connected to the inwardly extending webs of said end members. 80 85

In testimony whereof, I have signed my 90 name to this specification, in the presence of two subscribing witnesses.

ISAAC E. PALMER.
